DESIGN FOR A SHOETREE

Charles E. Harriman, West Bridgewater, Mass.,
assignor to Jones & Vining, Inc., Brockton,
Mass., a corporation of Massachusetts

Application May 29, 1940, Serial No. 92,683

Term of patent 7 years

To all whom it may concern:

Be it known that I, Charles E. Harriman, a citizen of the United States and a resident of West Bridgewater, county of Plymouth, and State of Massachusetts, have invented a new, original, and ornamental Design for a Shoetree, of which the following is a specification, reference being made to the accompanying drawing, forming part thereof.

In the drawing:

Fig. 1 is a view in perspective of my shoetree showing my new design; and

Fig. 2 is a side view of the same.

I claim:

The ornamental design for a shoetree, as shown.

CHARLES E. HARRIMAN.
